(57) **CLAIM**

I claim, the ornamental design for an interchangeable ornaments ring, as shown and described.

DESCRIPTION

FIG. 1 is a top perspective view of an interchangeable ornaments ring showing my new design;

FIG. 2 is a top plan view thereof;

FIG. 3 is a bottom plan view thereof;

FIG. 4 is a side elevational view thereof;

FIG. 5 is a front elevational view thereof;

FIG. 6 is a top perspective view shown in an environment;

FIG. 7 is a top perspective view shown in an alternate environment;

FIG. 8 is a top perspective view shown in an alternate environment;

FIG. 9 is a top perspective view shown in an alternate environment;

FIG. 10 is a top perspective view shown in an alternate environment;

FIG. 11 is a top perspective view shown in an alternate environment;

FIG. 12 is a top perspective view shown in an alternate environment;

FIG. 13 is a top perspective view shown in an alternate environment;

FIG. 14 is a top perspective view shown in an alternate environment; and,

FIG. 15 is a top perspective view shown in an alternate environment.

The broken lines shown in FIGS. 6-15 show environmental structure and form no part of the claimed design.

The surface shading lines indicate the contours of the surfaces.
